UNITED STATES PATENT OFFICE.

WILLIAM H. PATTERSON, OF NEW ORLEANS, LOUISIANA, ASSIGNOR TO AMERICAN SHEET METAL WORKS, A CORPORATION OF LOUISIANA.

ROOF-CLIP.

1,292,509.

Specification of Letters Patent. Patented Jan. 28, 1919.

Application filed April 4, 1916. Serial No. 88,774.

To all whom it may concern:

Be it known that I, WILLIAM H. PATTERSON, a citizen of the United States, residing at New Orleans, in the parish of Orleans and State of Louisiana, have invented certain new and useful Improvements in Roof-Clips, of which the following is a full, clear, and exact description.

This invention relates to fasteners for retaining roof sheets to the purlins of a roof. As is well known, the usual manner of fastening roof sheets to the purlins is by means of a clip which is attached to the purlin; a rivet passes through the clip and serves to secure the roof sheet to the clip. It has heretofore been proposed to permanently unite the clip and rivet and to so position the rivet upon the clip that the purlin acts as a support for the rivet while the same is being passed through the roof sheet and upset to fasten these parts together, this construction being desirable since it permits the roof sheets to be more quickly and readily fastened in place. It is the purpose of this invention to provide an improved form of fastener of this character which can be used with purlins whose flanges are directed toward the peak or eaves of the roof of a building and which will rigidly secure the roof sheets in position against lateral movement in either direction. It is also the object of the invention to provide a cheap and simple form of fastener which may be manufactured at a comparatively low cost.

With these objects in view, the invention consists in providing a substantially U-shaped clip having an offset extension through which the rivet is passed and secured thereto by brazing or in any other suitable manner, the head of the rivet fitting in the space provided by the offset portion whereby when the clip is secured to the flange of the purlin, the head of the rivet will rest upon the same and be supported thereby while the roof sheet is being fastened to the rivet. Two such clips may be utilized to secure a roof sheet to a purlin. One of these clips fits over the flange of the purlin as described while the other clip is oppositely disposed and has its free leg abutting against the vertical web of the purlin and has its offset extension extending over the flange so that the head of the rivet also rests upon the top flange of the purlin.

When the roof sheet is fastened to both

rivets, these clips, due to their engagement with the purlin, will prevent the roof sheet from lateral movement in either direction, and will therefore provide a very secure means for fastening the roof sheets in position.

In the accompanying drawings:

Figure 1 shows a rafter of a roof supporting the purlins with a roof sheet attached thereto in accordance with the principles of my invention;

Fig. 2 is an enlarged view showing the clip fitting over the flange of the purlin and the roof sheet in a position to be secured to the same, the purlin being shown in section;

Fig. 3 is a front elevation of Fig. 2, showing the roof sheet attached to the rivet;

Fig. 4 shows a clip abutting against the vertical web of the purlin, the clip which fits over the flange of the purlin being shown in dotted lines;

Fig. 5 is a perspective view of the clip; and

Fig. 6 is a similar perspective view of a slightly modified form of clip.

As is usual in roof constructions, the roof sheets are supported upon purlins which run transversely to the rafters 1 of the building, one of these rafters being shown in Fig. 1. The purlins 2 generally consist of strips of channel iron and comprise a vertical web 2' and flanges 3. The purlins are usually positioned so that their flanges are pointed toward the peak of the roof as in Fig. 1. The roof sheets which have been designated 4 are supported upon the purlins and are fastened thereto by means of rivets which pass through clips which are adapted to be secured to the purlins. These clips are in accordance with this invention constructed from a flat piece of metal which is stamped into the form shown in Fig. 5 providing a U-shaped part designated 5 and an offset extension 6, the offset extension being connected to one of the legs of the U-shaped part by means of an angularly-disposed portion 7. The amount of offset is sufficient to provide a space for the head 8 of a rivet 9, the shank of which passes through a suitable opening in the offset portion of the clip. The rivet is permanently secured to the offset extension which may be accomplished by brazing the shank of the rivet within the

opening through which it passes, or as shown in Fig. 6, by upsetting the extension as at the points 10 to wedge or clinch the clip around the shank of the rivet. The rivet may also be permanently secured to the clip in any other suitable manner.

Where the flanges of the purlins point toward the peak of the house, the clips are affixed to the top flanges of the purlins as shown in Fig. 2, the U-shaped portion of the clip fitting over the end of the flange, while the offset extension is directed toward the web of the flange so that the head of the rivet rests directly upon the top flange. In this position the purlin serves as a block or anvil to support the head of the rivet while the roof sheet is being fastened to its shank. This is accomplished by placing the roof sheet over the rivet as is shown in Fig. 2 and then forcing the end of the shank of the rivet through the roof sheet, the roof sheets being made of comparatively thin sheet metal which is usually corrugated to give it strength. A head is then formed on the shank of the rivet with a pneumatic riveter or in any other desired manner.

Where the flanges of the purlins point toward the eves of the building, the clips are arranged as is shown in Fig. 4. In this construction the end of the free leg of the U-shaped portion abuts against the vertical web of the purlin and the head of the rivet rests upon the top flange. The roof sheets are fastened to the rivets in the manner previously described. However, to prevent

the roof sheets from being raised from the purlins, additional clips are supplied which are fitted over the flange in the manner shown in Fig. 2, or as is shown in dotted lines in Fig. 4. It is desirable to proportion the clips so that the rivets of both clips will be in alinement and will pass through the top of the convexed portion of the corrugated roof sheets. If the roof sheets are not corrugated this is not important.

I claim:

1. A roof clip having two legs adapted to embrace a part of a purlin, an extension rising from one leg to engage a portion of a roof sheet elevated from the purlin, and a rivet whose shank projects upward through said extension to engage the roof sheet and having a head extending downward and adapted to rest directly upon the purlin.

2. A roof clip having two legs adapted to embrace a part of a purlin, an extension which rises from one leg to engage a portion of a roof sheet elevated from the purlin and which over-reaches the other leg of the clip, and a rivet whose shank projects upward through said extension to engage the roof sheet and having a head extending downward and adapted to rest directly upon the purlin.

In witness whereof, I subscribe my signature in the presence of two witnesses.

WILLIAM H. PATTERSON.
